UNITED STATES PATENT OFFICE.

HORACE H. RAYMOND, OF BERLIN, CONNECTICUT, ASSIGNOR TO THE STANDARD SAFETY MFG. CO., INC., OF NEW HAVEN, CONNECTICUT, A CORPORATION.

SAFETY DEVICE FOR FOOT-POWER PUNCH PRESSES AND LIKE MACHINES.

Application filed June 23, 1927. Serial No. 200,848.

This invention relates to an improvement in safety devices for foot-power punch-presses and like machines, and particularly to safety devices for preventing the movement of the punch or cutting tool of such a machine, in the event that the hand of the operator is in the path of the tool.

The object of this invention is to produce a simple, reliable and sensitive device of the 10 class described, constructed with particular reference to fewness of parts and low cost for manufacture.

With this object in view, my invention consists in a safety device for foot-power punch-presses and like machines, characterized by 15 having a stationary locking-bar adapted to be secured to the machine-frame and formed with locking-teeth; a bodily-movable swinging locking-lever pivotally mounted upon the 20 slide of the machine and also formed with locking-teeth; a guard-supporting rod carried by the said slide, with capacity for independent reciprocation with respect thereto; and a cam actuated by the said rod, where- 25 by the teeth of the swinging locking-lever are caused to co-act with the teeth of the stationary bar to positively stop the descent of the slide when the said guard-supporting rod is prevented from descending with the slide.

30 In the accompanying drawings:

Fig. 1 is a view in front elevation of the head and slide of a punch-press provided with my improved safety device;

Fig. 2 is a broken view thereof in side elevation;

Fig. 3 is a broken plan view thereof;

Fig. 4 is a sectional view on the line 4—4 of Fig. 1; and

Fig. 5 is a broken sectional view on the line 40 5—5 of Fig. 1.

In carrying out my invention as herein shown, I employ a vertically-arranged stationary locking-bar 10 provided at the opposite ends of its rear face with two rearwardly-projecting integral spacing-lugs 11 which bear against the front face of the left-hand side of the head 12 of a punch-press or similar machine, to which the bar is secured by means of screws 12^a passing through the said bar and lugs and into the head 12, as shown in the drawings. Upon its right edge, the locking-bar 10 just described is provided with a long vertical series of upwardly-facing angular teeth 13 for the purpose as will hereinafter appear.

The head 12 of the punch-press is of ordinary and well-known construction and carries the usual reciprocating slide 14 which mounts, at its lower end, a punch 15 or other suitable tool. Secured to the forward face of the slide 14 I mount a carrier-plate 16 which is provided at its opposite ends with two forwardly-projecting guide-lugs 17 and 18 which are formed respectively with vertical guide-passages 19 and 20 for the guidance of a vertically-arranged reciprocatable guard-supporting rod 21, which latter has capacity for 60 sliding movement in the said lugs and is provided, at its lower end, with an offsetting guard-ring 22 arranged annularly around the punch 15. The forward face of the guard-supporting rod 21 is formed with a series of transverse grooves 23, any one of which, as may be required, is adapted to receive the tapered inner end 24 of a coupling-pin 25 mounted in a horizontal bearing-opening 26 in the forward face of a cam-block 27 which is also formed with an inclined cam-face 28, as clearly shown in Fig. 1, and serves to limit the downward movement of the rod 70 21 by engaging the upper face of the lug 18. At its outer end, the coupling-pin is provided with a knurled finger-button 29 and midway of its length with an annular groove 30 into which extends the bifurcated outer end of a 80 bowed spring 31, the opposite end of which is secured to the right-hand end of the cam-block 27 by means of a screw 32.

The coupling-pin 25 just above mentioned serves to couple the cam-block 27 with the 90 guard-supporting rod 21 in any one of several positions of adjustment, so that the cam-block, in the normal functioning of the safety device, virtually constitutes a part of the said guard-supporting rod; the spring 31 exerting a constant effort to hold the tapered end 24 of the coupling-pin in engagement with one of the said coupling-grooves 23 of the guard-supporting rod 21.

The cam-face 28 of the cam-block 27 contacts with a cam-surface 33 formed upon one edge of a swinging locking-lever 34 near the lower end thereof and opposite to a series of downwardly-pointed angular teeth 35 which are formed upon its left edge, as clearly 105 shown in Fig. 1. The said locking-lever 34 is mounted for swinging movement upon the enlarged outer end 36 of a stud 37 provided with a threaded shank 38 passing through a clearance-passage 39 and entering a concen- 110

tric threaded bore 40 in the front face of the reciprocating slide 14 aforesaid. The junction of the parts 36 and 38 of the stud results in the formation of a rearwardly-facing shoulder 41 which bears in a shallow recess 42 in the forward face of the carrier-plate 16, concentric with the clearance-passage 39 therein and in line with the threaded bore 40 in the slide 14. The stud 37, just mentioned, 10 in conjunction with a screw 43, serves to attach the carrier-plate 16 to the slide 14.

At its extreme upper end, the swinging locking-lever 34 is provided with a forwardly and laterally-offsetting arm 44 mounting a 15 disk-like counterweight 45 which tends to swing the said lever from left to right, so that its teeth 35 are normally held out of engagement with the teeth 13 of the stationary locking-bar 10.

20 Under ordinary circumstances, the slide 14 descends to engage the punch 15 of the work and carries with it the carrier-plate 16, together with the locking-lever 34, cam-block 27, guard-supporting rod 21 and guard-ring

25 22. If, however, the hand of the operator has not been removed from the path of the punch 15, the guard-ring 22 will strike the hand, with the result that its downward movement, together with that of the guard- 30 supporting rod 21 and cam-block 27, will be checked. The continued downward movement of the locking-lever 34 with the slide 14 to which it is attached, will, by virtue of the engagement of its cam-surface 33 with the

35 cam-face 28 of the cam-block 27, cause the said locking-lever to be swung from right to left, so as to engage its downwardly-facing teeth 35 with the upwardly-facing teeth 13 of the stationary locking-bar 10, so that the

40 downward movement of the slide is positively checked until such time as the hand is removed from beneath the guard-ring 22, and the rod 21 and cam-block 27 permitted to descend into their normal positions with respect to the locking-lever 34, whereby the 45 same is permitted, under the urge of its counterweight 45, to swing its teeth 35 out of engagement with the teeth 13. When the descent of the rod 21 is checked by the inter-

50 position of the operator's hand, as above described, the guide-lugs 17 and 18 slide over the said rod. The number of teeth upon the locking-bar and locking-lever may vary, though, as shown, one of these locking elements is preferably provided with a larger number than the other, in order to insure a locking action at any point in the relatively long travel of the slide.

55 As thus constructed and described, my improved safety device effects the stoppage of the downward movement of the punch 15 or other tool which this slide 14 may carry without sensibly affecting the hand of the operator, since only the downward movement of the relatively-light parts 21, 22 and 27 must

be stopped by the hand in order to cause the teeth 35 to engage the teeth 13 and thus positively check the descent of the punch.

I claim:

1. The combination with the slide and head 70 of a foot-power punch-press or like machine; of a safety device comprising a stationary locking-bar secured to the front face of the said head and provided in its side-edge with locking-teeth; a swinging locking-lever also 75 provided in its side-edge with locking-teeth and carried by the said slide so as to swing laterally across the front face thereof; means for holding the locking-teeth of the said lever out of engagement with the locking-teeth of the said bar; a vertically-movable guard-supporting rod also carried by the said slide with capacity for independent movement with respect thereto; and a cam actuated by the said rod; whereby the locking-lever is 80 caused to swing crosswise of the slide and co-act with the teeth of the stationary bar to positively stop the descent of the slide when the said guard-supporting rod is prevented from descending with the slide. 90

2. The combination with the slide and head of a foot-power punch-press or like machine; of a safety device comprising a stationary locking-bar secured to the front face of the said head and provided in its side-edge with locking-teeth; a swinging locking-lever also 95 provided in its side-edge with locking-teeth and carried by the said slide so as to swing laterally across the front face thereof; means for holding the locking-teeth of the said lever out of engagement with the locking-teeth of the said bar; a vertically-movable guard-supporting rod also carried by the said slide with capacity for independent movement with respect thereto; and a cam co-acting with the 100 said lever and adjustably connected to the said rod; whereby the locking-lever is caused to swing crosswise of the slide and co-act with the teeth of the stationary bar to positively stop the descent of the slide when the said 105 guard-supporting rod is prevented from descending with the slide. 110

3. The combination with the slide and head of a foot-power punch-press or like machine; of a safety device comprising a stationary 115 locking-bar secured to the front face of the said head and provided with locking-teeth; a carrier-plate secured to the front face of the said slide adjacent the said locking-bar; a swinging locking-lever also provided with locking-teeth and pivotally mounted upon the said carrier-plate for movement across the front face thereof; means for holding the locking-teeth of the said lever out of engagement with the locking-teeth of the said bar; a vertically-movable guard-supporting rod also carried by the said carrier-plate with capacity for independent movement with respect thereto; and a cam actuated by the said rod; whereby the locking-lever is 120 125 130

caused to swing across the front face of the slide and coact with the teeth of the stationary bar to positively stop the descent of the slide when the said guard-supporting rod is prevented from descending with the slide.

4. The combination with the slide and head of a foot-power punch-press or like machine; of a safety device comprising a stationary locking-bar secured to the front face of the 10 said head and provided with locking-teeth; a carrier-plate secured to the front face of the said slide adjacent the said locking-bar and provided with a pair of guide-lugs; a swinging locking-lever also provided with 15 teeth and pivotally mounted upon the said carrier-plate for movement across the front face thereof; means for holding the locking-teeth of the said lever out of engagement with the locking-teeth of the said bar; a guard- 20 supporting rod reciprocably mounted in the said guide-lugs with capacity for independent movement with respect to the said carrier-plate; and a cam mounted upon the said rod in position between the said guide-lugs; 25 whereby the locking-lever is caused to swing crosswise of the slide and co-act with the teeth of the stationary bar to positively stop the descent of the slide when the said guard-supporting rod is prevented from descending 30 with the slide.

5. The combination with the slide and head of a foot-power punch-press or like machine; of a safety device comprising a stationary locking-bar secured to the front face 35 of the said head and provided with locking-teeth; a swinging locking-lever pivotally mounted on the said slide for movement across the front face thereof and formed on one edge with locking-teeth and on its op- 40 posite edge with a cam-surface; a counterweight laterally offsetting from the said lever in position to normally urge the locking-

teeth of the said lever away from the locking-teeth of the said bar; a vertically-movable guard-supporting rod also carried by the said 45 slide with capacity for independent movement with respect thereto; a cam carried by the said rod and co-acting with the cam-surface on the said lever; whereby the locking-lever is caused to swing crosswise of the slide 50 and co-act with the teeth of the stationary bar to positively stop the descent of the slide when the said guard-supporting rod is prevented from descending with the slide.

6. The combination with the slide and head of a foot-power punch-press or like machine; of a safety device comprising a stationary locking-bar secured to the front face of the 55 said head and provided with locking-teeth; a carrier-plate secured to the front face of the said slide adjacent the said locking-bar; a swinging locking-lever pivotally mounted upon the said carrier-plate for movement across the front face thereof and formed on one edge with locking-teeth and on its opposite edge with a cam-surface; a counterweight 60 laterally offsetting from the said lever in position to normally urge the locking-teeth of the said lever away from the locking-teeth of the said bar; a vertically-movable guard-supporting rod also carried by the said carrier-plate with capacity for independent movement with respect thereto; and a cam carried by the said rod and co-acting with the 65 said cam-surface; whereby the locking-lever is caused to swing crosswise of the said plate and co-act with the teeth of the stationary bar to positively stop the descent of the slide when the said guard-supporting rod is prevented from descending with the slide.

In testimony whereof, I have signed this specification.

HORACE H. RAYMOND.
